Assistant Examiner — Shawn T Gingrich

(57) **CLAIM**

The ornamental design for a connector for power cable, substantially as shown and described.

DESCRIPTION

FIG. 1 is a front view of a connector for power cable embodying our new design, a back view thereof being a mirror image;

FIG. 2 is a plan view thereof;

FIG. 3 is a bottom view thereof;

FIG. 4 is a right side view thereof; and,

FIG. 5 is a left side view thereof.

The broken line portion of the figure drawings is included to show portions of the article that form no part of the claimed design.

1 Claim, 3 Drawing Sheets
